UNITED STATES PATENT OFFICE.

SEWARD HOMER CALKINS, OF BALTIMORE, MARYLAND.

SHEET-METAL TILE.

No. 857,718.

Specification of Letters Patent.

Patented June 25, 1907.

Application filed March 21, 1907. Serial No. 363,606.

To all whom it may concern:

Be it known that I, SEWARD HOMER CALKINS, a citizen of the United States, residing at Baltimore, in the State of Maryland, have 5 invented certain new and useful Improvements in Sheet-Metal Tiles, of which the following is a specification.

This invention relates to improvements in the construction of tiles for wall finish.

10 The invention has several objects in view; one object being to provide the tile on its opposite edges with backward projecting flanges which incline inwardly for the several purposes of (1) forming at the back of the tile what may be termed an "undercut" with which the plastic cement on the wall may engage to effect a secure bond, (2) forming edges which are beveled or recede from the front surface so that at the front the 15 edges of adjoining tiles will closely abut, and (3) forming concealed spaces between the edges of adjoining tiles, which spaces may be filled after the tiles have been placed in position by injecting cement in a semi-fluid condition.

20 The improved tile is constructed with the view of being set in plastic cement on the wall, or nailed to a wood surface. It is well understood that this class of tile may be 25 glazed, painted or enameled in any color.

The drawings illustrate the invention.

Figure 1 is a front perspective view of an improved tile having the features of my invention. Fig. 2 is a back view of the tile shown in Fig. 1. Fig. 3 is an outer or front view of several tiles as they appear when being placed in position. Fig. 4 shows a top view of one side edge of a tile. Fig. 5 is a horizontal section taken on the line 5—5 of Fig. 3 showing the position of a joint of two tiles above the central cut-out portion of the tile next below. Fig. 6 is a sectional view on a larger scale of one tile and the ends of two adjoining tiles, and the cement on the wall, 40 to show the relation of the various parts. Fig. 7 is a back view of a tile having the features of my invention, but modified from the form shown in Figs. 1 to 6 inclusive, by having one bend less in the edge-flange. Fig. 8 is a front perspective view of the tile shown in Fig. 7. Fig. 9 is a cross-section of the tile shown in Figs. 7 and 8.

Inasmuch as all the features of the form of tile shown in Figs. 7, 8 and 9 are also in the other form shown in Figs. 1 to 6 of the drawing, I will first describe the construction of

the form illustrated in said Figs. 7, 8 and 9, and then it will only be necessary to describe the additional features of the tile shown in Figs. 1 to 6.

Referring to Figs. 7, 8 and 9 the outer or front face of the sheet-metal tile is designated by the numeral, 1, and in practice this face may be painted, japanned or enameled, and the back is designated, 2. The opposite edges of the tile are provided with a flange, 3, which from the front face projects backward and also inclines inwardly thereby forming as shown in Fig. 9, what may be termed an "undercut," when the back, 2, of the tile is pressed against plastic cement on the wall, the cement will engage with the said undercut part, 4, of the flange, 3, and when the cement has "set" or hardened it will securely hold the tile. This beveling of the flange, 3, from the front face also results in forming prominent edges, 5, at the front which insures that the edges of adjoining tiles will abut closely and make close fitting joints at the front. It will also be understood that when the prominent edges, 5, of two of these beveled or backward-receding flanges are in contact, they will form a triangular shaped concealed space by the edge of one inclined flange, 3, of one tile bearing 85 on or in contact with a flat lateral flange, 8, of the adjoining tile. This is plainly shown in Fig. 6, where the concealed space is designated, 6. The concealment here referred to is concealment from front view after the tile 90 have been set. Those spaces, 6, serve a useful purpose in that they afford room for the reception of semifluid cement which may be injected or placed in the spaces during the operation of securing the tiles in position. 95 The semifluid cement will harden in the space, 6, and make a perfectly tight joint. The backward-projecting flanges, 3, may be on all the edges of the tile but at least are on opposite edges, therefore one or more of said flanges have a notch, 7, which serve to vent 100 the air from behind the tile when pressing the tile closely in contact with the plastic cement on the wall. It will also be seen by reference to Figs. 7, 8 and 9 that a flange, 8, 105 projects laterally from the bevel flange, 3, at one side and one end and said lateral flange, 8, is in a plane that is parallel with the plane of the front face, 1. Where the tile is rectangular the said lateral flange, 8, will project from but two edges; the other two edges will have only the beveled flange, 3. In

order to permit of securing the tile to a wood surface the lateral flanges, 8, have perforations, 9, to receive small nails. When the tiles are in position on a wall, the edge of 5 bevel flange, 3, at two right-angled edges of the tile, will bear on the flat lateral flanges, 8, of two adjoining tiles and conceal them, as will be understood by reference to Fig. 3, because in that figure a front view of three 10 tiles are shown in set position.

For a description of the features of the sheet-metal tile shown in Figs. 1 to 6 it is to be understood that all that has been stated with regard to Figs. 7, 8 and 9 are applicable. 15 The tile shown in Figs. 1 to 6 however, has some additional features, which will now be described. A flange, 10, is bent from or attached to the lateral flange, 8; this flange, 10, projects at a right angle with respect to 20 the flange, 8, and is also at a right angle with respect to the front face, 1, of the tile as seen in Figs. 1 and 6. The part in these Figs. 1 to 6, that corresponds to the lateral flange, 8, in Figs. 7, 8 and 9 has a central cut-out portion, 25 11, and the ends of the said flange, 8, at each side of the cut-out are bent back to form bevels as at, 12, thus making the cut-out nearest the outer or front surface broader than at the back. In placing the tiles against 30 plastic cement and applying pressure, the cement will press through the narrow back part of the cut-out portion and spread forward into the broader part of the same, and form a bond or key.

From the description herein given the 35 manner of applying the tiles or placing them in position will be understood.

Having thus described my invention what I claim as new and desire to secure by Letters Patent is, —

1. The combination of two tiles each having on all of its opposite edges a flange, 3, which projects backward and also inclines inwardly and forms at the back parallel opposing undercuts, and two of said adjoining 45 inclined flanges provided with an outward lateral flange, 8, which has position in a plane parallel with the front face of the tile, and the edge of one of said inclined flanges, 3, of one tile bearing on or in contact with a 50 flat lateral flange, 8, of the other tile, thereby forming a joint having a concealed space.

2. A sheet-metal tile having around its edges a flange projecting backward and also inclining inwardly and forming an undercut 55 surrounding its edges, and two of said inclined flanges provided with an outward border flange, 8, whose surface is parallel with the front face of the tile, and a flanged edge, 10, projecting at a right-angle with respect to the said border flange, 8.

In testimony whereof I affix my signature in presence of two witnesses.

SEWARD HOMER CALKINS.
